(57) **CLAIM**

The ornamental design for a wristband health tracker, as shown and described.

DESCRIPTION

FIG. 1 is an isometric view of a wristband health tracker looking at the top, front, and right sides.

FIG. 2 is a further isometric view of the wristband health tracker looking at the top, back, and right sides.

FIG. 3 is a further isometric view of the wristband health tracker looking at the bottom, back, and left sides.

FIG. 4 is a further isometric view of the wristband health tracker looking at the bottom, front, and left sides.

FIG. 5 is a left side view of the wristband health tracker.

FIG. 6 is a right side view of the wristband health tracker.

FIG. 7 is a front view of the wristband health tracker.

FIG. 8 is a back view of the wristband health tracker.

FIG. 9 is a bottom view of the wristband health tracker.

FIG. 10 is a top view of the wristband health tracker; and,

FIG. 11 is an isometric view of the wristband health tracker looking at the top, front, and right sides.

Stipple shading is used in FIGS. 1 through 11; the stipple shading is not be understood as conveying a particular surface finish. The surface finish may be smooth/gloss, satin, or textured. The depicted articles may be made using materials of various colors, including black, charcoal, white, dark blue, lime, magenta, and other colors. A portion on the top side of the wristband health tracker that does not have the diagonal ridge pattern on the wristband portions is a translucent, clear, or clear, tinted material, as indicated by the diagonal line hatching on that portion.

The broken line showing of structural features is included for the purpose of illustrating non-claimed subject matter and forms no part of the claimed design.
